UNITED STATES PATENT OFFICE.

FERDINAND PIASZEK, OF SAGINAW, MICHIGAN.

DESIGN FOR A LENS.

Application filed February 28, 1922. Serial No. 934. Term of patent 14 years.

To all whom it may concern:

Be it known that I, FERDINAND PIASZEK, a citizen of the United States, residing at Saginaw, Saginaw County, Michigan, have invented a new, original, and ornamental Design for Lenses, of which the following is a specification, reference being had to the accompanying drawing, forming part thereof.

The drawing is a plan view, showing my

new design, consisting in a glass disk, parts of the surface of which are opaqued, as by sand blasting, the opaqued parts being shown as shaded in the drawing.

I claim the ornamental design for a lens as shown.

FERDINAND PIASZEK. [L. S.]
